UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,135, dated September 29, 1896.

Application filed August 24, 1896. Serial No. 603,793. Term of patent 3½ years.

To all whom it may concern:

Be it known that I, CHARLES BOOZ, a citizen of the United States, residing at Buffalo, in the county of Erie and State of New York, 5 have invented and produced a new and original Design for Wall-Paper, of which the following is a specification, reference being had to the accompanying drawing, showing a part thereof.

10 The design consists of large groups of roses and leaves with vines of flowers and leaves diverging right and left from the bottom of said groups of roses and leaves, as represented in the accompanying drawing.

15 The border for the said design is also formed of large groups of roses arranged in panels formed of interlacing vines of flowers and leaves with a line of flowers and leaves connecting said panels, as shown in the drawing.

What I claim is—

1. The design for wall-paper herein shown and described.

2. In the design for wall-paper, the border herein shown and described.

Witness my hand this 10th day of August, 25 1896.

CHARLES BOOZ.
